UNITED STATES PATENT OFFICE.

WALTER F. CUSHING, OF BISMARCK, NORTH DAKOTA.

MAGAZINE-PENCIL.

No. 878,771.

Specification of Letters Patent.

Patented Feb. 11, 1908.

Application filed July 2, 1906. Serial No. 324,427.

To all whom it may concern:

Be it known that I, WALTER F. CUSHING, a citizen of the United States, residing at Bismarck, in the county of Burleigh and State of North Dakota, have invented certain new and useful Improvements in Magazine-Pencils, of which the following is a specification.

My invention relates to an improvement in magazine pencils, and the object is to provide a very light, simple device of trifling cost to manufacture, and durable and efficient for the purpose for which it is designed.

With the foregoing objects in view, my invention consists in a metal tube split or having a narrow slit throughout a portion of its length, which slit is provided with diagonal notches at one side in connection with an inner sliding tube adapted to fit and have an extended bearing in the barrel, and carrying the pencil lead at one end, removable therein with a spring supported thumb piece at the other adapted to pass through the slit of the barrel and lock itself in the notches therein.

My invention further consists in a rubber or yielding cone for yieldingly gripping the lead and holding it in the end of the inner tube or cylinder.

It further consists in a specially constructed sharpener for the lead which sharpener forms a cap for the pencil when in place thereon and serves the secondary function of preventing the split portion thereof from spreading.

My invention further consists in certain novel features of construction and combinations of parts which will be hereinafter described and pointed out in the claims.

In the accompanying drawings: Figure 1 is a longitudinal, sectional view through the magazine pencil. Fig. 2 is a top plan view. Figs. 3, 4 5 and 6 are details.

A, represents the barrel of the pencil which is preferably made of thin metal cylindrical in form and of a length to suit the requirements, tapering at the forward end as at 1, and made solid within this tapering end to secure suitable and lateral support at that point for the lead 2. This outer tube is provided with a hair line slot or slit 3 which extends from the rear end some distance toward the opposite end but preferably leaving a solid cylindrical portion between its inner end and the point of the tube 55 as shown, to be gripped between the thumb and fingers. One side of this hair line slit or

slot is straight and the other is provided with diagonally disposed notches or ratchet teeth 4.

The barrel is open at the end opposite from the point and a cylindrical tube or carrier 5 of suitable length is fitted to slide in the barrel. In one end of this tube or cylinder the lead 2 is removably gripped by means of a truncated rubber cone 7, the special function of which rubber cone is that it holds the lead tightly in place but affords sufficient elasticity to permit it to yield as necessity requires and especially gives greater freedom for the longitudinal movement of the lead 70 when in use, thus avoiding the danger of breakage at this point, which is likely to result from too rigid a clamp as by metal, which ultimately causes the lead to erode resulting in its falling out, but the rubber gives 75 a tight grip while permitting it to yield sufficiently for all purposes and the grasp may be tightened by simply forcing the cone further in place.

At the opposite end of the tube or carrier 80 the thumb piece 8 is formed upon a flat steel spring 9. This spring is very thin, and sets slightly diagonal, its function being to slide through the slit of the barrel and spring into the nearest notch automatically, thus holding the lead in place and permitting it to be fed forward as it wears and is re-sharpened.

To remove the tube or carrier with any remaining unused lead, the thumb piece is slightly twisted and the spring 9 brought 90 parallel with the straight edge of the slit or slot in the barrel, whereupon the carrier with the lead is capable of being removed from the barrel with perfect ease.

A cap C is adapted to be held frictionally 95 upon the end of the barrel. This cap preferably carries an eraser 10, at its outer end, and pencil sharpener 11, at its inner end, and it has, consequently, the function of holding the slit upon the end of the barrel A closed, 100 while guarding the sharpener when thus in place. The sharpener consists of a small steel knife cast in lead or other metal, diagonally to the slant or the point cone, said cone being set in the sharpener so that the sharpener projects into the barrel of the pencil when not in use, giving it a small and compact form and protecting the sharpener. 105

The special merits of my improved pencil will be readily understood from the foregoing description, but in conclusion, it might be mentioned that it is designed to carry a 110

single lead, thus reducing the weight to a minimum and preventing annoyance of rattling so common to pencils of the magazine type, when in use; it is very simple in construction, and the cost of manufacture is trifling. The barrel has comparatively few notches and these are started far enough back so as to leave ample space beneath for the fingers and thumb to grasp. Without 10 removing the pencil from the hand, the lead can be advanced the desired distance by merely pressing the thumb on the thumb piece and forcing it forward the distance of one or more notches. The slot or slit is so 15 small that it precludes the entrance of dirt or other extraneous matter. By the use of the solid end and the rubber or elastic cone, the dropping of the pencil is not apt to cause the lead to break, even if it should strike 20 point down.

Slight changes might obviously be made in the form and arrangement of the various parts described without departing from the spirit and scope of my invention, and hence 25 I do not wish to limit myself to the exact construction herein set forth; but,

Having fully described my invention, what I claim as new and desire to secure by Letters Patent, is:—

- 30 1. As an article of manufacture, a magazine pencil comprising a barrel having an open slot extending lengthwise thereof, said slot having one notched edge, a removable lead carrier fitting the bore of the barrel and adapted to be slid therein, a thin spring secured to the carrier at a point remote from the slot in the barrel, said spring set diagonally whereby normally to engage the notches on the edge of the slot, a thumb piece secured to the outer end of the spring, the spring being sufficiently yielding so that a lateral twist of the thumb piece will remove it from the notched edge of the slot.
- 45 2. As an article of manufacture, a magazine pencil comprising a barrel having an open slot extending lengthwise thereof, said slot having one notched edge, a removable lead carrier fitting the bore of the barrel and adapted to be slid therein, a thin spring secured to the carrier at a point remote from the slot in the barrel, said spring set diagonally whereby normally to engage the notches on the edge of the slot, a thumb piece secured to the outer end of the spring, the spring being sufficiently yielding so that a lateral twist of the thumb piece will remove it from the notched edge of the slot, and a removable

cap for closing the open end of the slot in the barrel.

3. As an article of manufacture, a magazine pencil comprising a barrel having an open slot extending lengthwise thereof, said slot having one notched edge, a removable lead carrier fitting the bore of the barrel and adapted to be slid therein, a thin spring secured to the carrier at a point remote from the slot in the barrel, said spring set diagonally whereby normally to engage the notches on the edge of the slot, a thumb piece secured to the outer end of the spring, the spring being sufficiently yielding so that a lateral twist of the thumb piece will remove it from the notched edge of the slot, and a removable cap for closing the open end of the slot in the barrel, said cap carrying a pencil sharpener at one end and an eraser at the other.

4. As an article of manufacture, a magazine pencil having a tapering slot at one end to afford lateral support for the lead, and a rubber cone for clutching and holding the lead at its opposite end.

5. In a magazine pencil, the combination with a barrel, of a carrier fitted to slide therein and a cone of soft elastic material adapted to carry the lead attached to the carrier.

6. The combination with a barrel having a narrow slot extending throughout a portion of its length straight on one side and notched on the other, of a lead carrier having means at one end for locking in different positions in the barrel, and a rubber cone removably held in the opposite end of the carrier and adapted to clutch one end of the lead therein.

7. In a magazine pencil, the combination with a barrel, of a cylindrical tube or carrier fitted to and sliding in the barrel, a cone of soft elastic substance held in one end of the carrier and having lead inserted therein, and a spring thumb piece connected with the carrier whereby it is moved and locked in the barrel.

8. In a magazine pencil, the combination with a barrel, of a carrier fitted to slide therein and a rubber cone fitted within the pencil and having one end of the lead inserted therein.

In testimony whereof I have signed my name to this specification in the presence of two subscribing witnesses.

WALTER F. CUSHING.
